UNITED STATES PATENT OFFICE.

CLARENCE BOGERT, OF DEMAREST, NEW JERSEY.

DESIGN FOR A BUBBLE-BLOWER.

55,409.

Specification for Design.

Patented June 8, 1920.

Application filed January 9, 1920. Serial No. 350,452. Term of patent 7 years.

To all whom it may concern:

Be it known that I, CLARENCE BOGERT, a citizen of the United States, residing at Demarest, in the county of Bergen and State of New Jersey, have invented a new, original, and ornamental Design for Bubble-Blowers, of which the following is a specification, reference being had to the accompanying drawing, forming part thereof.

Figure 1 is a side elevation of a bubble blower, showing my new design.

Fig. 2 is a plan view thereof.

I claim:

The ornamental design for a bubble blower, as shown.

CLARENCE BOGERT.
